UNITED STATES PATENT OFFICE.

WILLIAM S. COOPER, OF PHILADELPHIA, PENNSYLVANIA.

WATER-CLOSET.

SPECIFICATION forming part of Letters Patent No. 249,903, dated November 22, 1881.

Application filed March 24, 1881. (Model.) Patented in England September 25, 1879.

To all whom it may concern:

Be it known that I, WILLIAM S. COOPER, a citizen of the United States, residing in Philadelphia, Pennsylvania, have invented certain 5 Improvements in Water-Closets, of which the following is a specification.

The main objects of this invention are to insure the proper flushing of the basin and pipes, to prevent the overflow of the basin, and to insure 10 a tight joint between the valves and the valve-seats on the basin-outlet and overflow-pipe and between the supply-pipe and basin-inlet. These objects I attain in the manner which I will now proceed to describe, reference being had to the accompanying drawings, 15 in which—

Figure 1, Sheet 1, is a longitudinal section of my improved water-closet; Fig. 2, Sheet 2, a plan view of the same; Fig. 3, Sheet 3, a 20 transverse section on the line 1 2, Fig. 2; Fig. 4, a transverse section on the line 3 4, Fig. 2; Fig. 5, Sheet 4, a longitudinal section, partly in elevation, of the water-supply valve; Fig. 6, a sectional plan on the line 5 6, Fig. 5; Fig. 7, a 25 transverse section on the line 7 8, Fig. 6; and Figs. 8, 9, and 10, detached views of parts of the closet, drawn to an enlarged scale.

A is the basin of the water-closet; B, the discharge-chamber; D, the valve for closing 30 the basin-outlet; E, the valve for controlling the admission of water to the basin, and F the weighted pull-rod for operating the lever G, whereby the valves D and E are opened and closed. This lever is connected to a rock-shaft, 35 a, having two arms, b and c, the arm b carrying the valve D, and the arm c being adapted to act upon a pivoted arm, d, whereby the spindle e of the valve E is elevated in order to open said valve and permit the flow of wa- 40 ter into the basin. The arm d has a curved portion, d', upon which the anti-friction roller on the arm c acts, this curved portion d' being so proportioned in respect to the center of the rock-shaft a that movement will be imparted 45 to the arm immediately upon the commencement of the opening movement of the valve D, so that water will flow through the basin as soon as the valve D begins to open.

The valve E is peculiarly constructed, (as de- 50 scribed hereinafter,) in order that it will close

slowly, so that water will continue to flow into the basin A for some time after the valve D is closed and the support of the arm d removed from the valve-stem e, a supply of water being thus allowed to accumulate in the basin, in order to flush the soil-pipe when the valve D is again opened. In order to prevent this supply of water from rising in the basin A to such a height as to overflow the top of the same, I arrange at one side of the basin an overflow-chamber, J, divided by partitions f into three compartments, g, g', and g'', the compartments g, g' containing floats h and i, respectively, and the compartment g'' communicating through a passage, j, with the discharge-chamber B of 65 the closet. The lower end of the passage j is closed by a valve, k, the rod of which is connected to the short arm of a lever, k', the long arm of which carries the float h.

The compartment g' communicates through 70 a passage, m, with the basin A, so that when the water rises in the basin to a point above this passage the compartment g' will be filled and the water will flow over the partitions f into the compartments g and g'', and the float 75 h will be raised so as to open the valve k and permit the surplus water to escape into the discharge-chamber B. When the supply is cut off the water will gradually be drained from the compartment g through the passage n, and as the float falls the valve k will be raised and the passage j closed, the weight of the float tending to keep the valve firmly pressed against its seat, and thus prevent the leakage of gases 80 between the two, the water which accumulates 85 in the passage j after the closing of the valve k being also of assistance in sealing the pipe against the passage of gas.

The water-supply valve E is similar in general construction and operation to that shown 90 in my Patent No. 132,523, dated October 29, 1872, having a grooved plunger, p, with loosely-fitting ring q, which during the downward movement of the plunger bears firmly against the upper flange of the same, and during the 95 upward movement of the plunger rests on the lower flange, in which are formed openings, as shown in Fig. 6. When the plunger is down the valve s rests on the seat s' and the passage of water to the basin A is prevented; 100

but when the rod *e* is elevated by the arm *d* the valve *s* is raised and water passes through the chest *E* and pipe *E'* to the said basin. As the plunger *p* rises with the valve *s*, any water which may be above said plunger passes around the ring *q* and through the openings in the lower flange of the plunger; but the instant the plunger commences to descend under the influence of the spring *s²*, so as to close the valve *s*, the ring *q* is forced firmly against the upper flange, and the descent of the plunger is retarded by the partial vacuum formed above the same, the only relief for this partial vacuum being the gradual inlet of water to the space above the plunger through the passages *t* *t'* and chamber *t²*, the rapidity of the flow being governed by the adjustment of the set-screw *t³*. It will thus be seen that the closing of the valve *s* is gradual, in order to effect the above-mentioned flow of water into the basin after the valve *D* of the same has been closed. It occasionally happens, however, that the supply of water is cut off or is insufficient to properly flush the basin during the time that the plunger *p* occupies in descending; hence I make provision for closing the relief-passage of the valve and holding the plunger in its elevated position until the basin has received a proper supply of water. The device which I employ for this purpose is a valve, *w*, Fig. 6, adapted to close the end of the passage *t* and acted upon by a plunger, *w'*, the latter being connected by means of the system of levers and rods shown in Fig. 1 to the float *i* in the compartment *g'* of the overflow-chamber *J* of the basin. When said float is down—that is to say, as long as the compartment *g'* is empty—the valve *w* will be closed and the flow of water through the passage *t* into the space above the plunger *p* will be prevented, so that said plunger cannot descend, and in consequence the valve *s* will be held open until such time as there is a flow of water into the basin *A* sufficient to fill the compartment *g'* of the overflow-chamber, raise the float *i*, and withdraw the plunger *w'*, so as to permit the opening of the valve *w* and the passage of water to the space above the valve-plunger *p*. The valve *D* of the basin has a rubber packing-ring, *x*, and the seat for this valve, and also that for the valve *k*, consists of a rubber ring, *y*, the inner edges of said rings *x* and *y* being recessed in order to form flanges *z*, gradually reduced to a thin edge, so that they will accommodate themselves to foreign matters introduced between the valve and seat and prevent leakage due to the presence of said foreign matters.

To one side of the casing of the discharge-chamber *B* of the closet is attached a tube, *P*, which may be connected by a suitable system of pipes with any adjacent ventilating-flue. The cap *Q* of this tube has a socket adapted for the reception of a ball at the end of the arm *d*, thus forming a pivot for said arm, the ball being retained in the socket by means of a screw-plug, *R*.

The end of the water-supply pipe *E'* which enters the projection *S* on the basin *A* is threaded, and to the end of this threaded projection is adapted a collar, *T*, packing *W* being interposed between this collar and a nut, *Y*, on the pipe *E'*, so that on screwing up said nut the packing will be compressed and expanded between the pipe and the interior of the projection *S*, thereby forming a tight joint without the use of the usual cements. 75

In carrying out my invention the float and the valve controlled thereby may be used in connection with other automatic valve-controlling devices than those shown. For instance, the valve *w* might be employed to cut off the flow of air through a passage to an expansion device connected with the supply-valve, said passage having, of course, a regulating valve or 85 screw for a purpose similar to that of the screw shown in applicant's valve.

I am aware that it has been proposed to connect the supply-valve of a water-closet with a float in an overflow-chamber, so that the valve 90 would be directly opened and closed by the movements of the float; but my invention differs from these, in that the float in the overflow-chamber has no direct connection with the supply-valve and does not affect the opening 95 of the same or directly control its closing, being simply to regulate the action of the devices whereby the valve is closed.

I claim as my invention—

1. The combination of the basin of a water-closet, the supply-valve, devices for automatically controlling the closing of the same, an overflow-chamber, *J*, a float arranged in said overflow-chamber, and a valve operated by said float and adapted to govern the operation of 100 said automatic controlling devices, as set forth.

2. The combination of the basin *A*, the overflow-chamber *J*, having float-compartment *g* and discharge-compartment *g²*, and a draining-passage, *n*, between said compartments, as set 110 forth.

3. The combination of the basin *A*, the overflow-chamber *J*, having a compartment, *g'*, communicating with the basin, the float *i*, arranged in said compartment and adapted to govern 115 the closing of the supply-valve, the compartment *g*, separated from the compartment *g'* by a partition, *f*, and the float *h*, arranged in said compartment *g*, and adapted to actuate the discharge-valve of the overflow-chamber, as set 120 forth.

4. The combination of the basin *A*, the floats *h* and *i*, and valve *k*, and overflow-chamber *J*, having compartments *g*, *g'*, and *g²*, arranged side by side and separated by partitions *f*, as 125 set forth.

5. The combination of the supply-valve *E* and its valve-rod *e* with the pivoted operating-arm *d*, having a curved portion, *d'*, and the rock-shaft *a*, having the valve-arm *b* and the arm *c* for actuating the arm *d*, as set forth.

6. The combination of the arm *d*, having an enlarged end, with the tubular extension *P* of the discharge-chamber *B* of the closet, having

a cap, Q, with socket adapted for the reception of said enlarged end of the arm, as set forth.

7. The combination of the valve and valve-seat of the closet with packing-rings, each having its inner edge recessed, as set forth, whereby a thin-edged bearing-flange, z, is formed, as specified.

8. The combination of the projection S of the basin, the supply-pipe E', having a threaded end, with collar T, the packing W, and the nut Y, whereby the packing is compressed and a tight joint formed, as set forth.

9. The combination of the overflow-chamber J, having the float-compartment g and outlet-passage j, the upwardly-closing valve k for said passage, the float h, and the lever k', connecting the float to the valve-rod, as set forth.

In testimony whereof I have signed my name to this specification in the presence of two subscribing witnesses.

WILLIAM S. COOPER.
